FASTENING DEVICE

Filed Feb. 11, 1932

UNITED STATES PATENT OFFICE

ALBERT H. TINNERMAN, OF CLEVELAND, OHIO

FASTENING DEVICE

Application filed February 11, 1932. Serial No. 592,377.

This invention relates to nut and bolt devices and particularly to a construction by means of which two articles may be fastened together by a bolt and nut, and where from the construction of the article, the nut cannot be held by the operator while the bolt is being turned. Situations of this character arise in the manufacture of hollow articles, as for example, refrigerator cabinets, metal furniture, automobile bodies and the like.

As applied to the manufacture of refrigerator cabinets, the procedure heretofore, has been to utilize a wooden frame that extends around the region adjacent the door opening and that forms the anchoring structure to which the closure plates are fastened. The same type of construction has been used for the door to hold the outer and inner plates in spaced relationship. The use of a wooden frame for such purpose is objectionable, for the wood deteriorates, the assemblies are expensive, the screws loosen and the finish becomes impaired. It has been regarded as necessary however, to use a wooden frame in constructing metallic cabinets in order that the structure would be completely enclosed and would have a hollow interior which could be suitably insulated against the conduction of heat.

An object of my invention is to provide a device by means of which a hollow structure may be quickly and economically assembled, notwithstanding the fact that the final fastening members must be positioned through blind openings. The invention has particular usefulness in the manufacture of hollow metallic articles, in that the various coacting parts may be progressively assembled, and then fastened together in an expeditious manner.

Referring now to the drawing, Fig. 1 is a perspective view of a device embodying my invention; Fig. 2 is a front elevation of a refrigerator cabinet, with which my invention can be used; Fig. 3 is a section taken on the line 3—3 in Fig. 2 but showing the door spaced from the cabinet; Fig. 4 is a section taken on an enlarged scale adjacent the corner of the cabinet and also showing the door spaced from the box; Fig. 5 is a section taken

on the line 5—5 in Fig. 1; Fig. 6 is an enlarged perspective view showing a modification of a device embodying my invention; Fig. 7 is a horizontal section through two strips of metal that are fastened together by means of the device that is illustrated in Fig. 6; Fig. 8 is a section through another modification of my invention, and Fig. 9 is a perspective view of the strip shown in Fig. 8.

While my invention is illustrated in connection with refrigerator cabinets, nevertheless it is applicable for use with other types of construction as hereinbefore stated. The cabinet, as shown, has an inner plate 10 and an outer plate 11 between which suitable heat insulating material 12 may be disposed. The marginal edges of the inner plate may be shaped to provide a flange 13 while the marginal edges of the outer plate may be shaped to provide a flange 14. The space between such flanges may then be closed by a plate 15 which extends around the edges of the door opening. The door construction likewise may embody an inner plate 16, and an outer plate 17 with insulation 18 therebetween and a closure strip 19 which coacts with the strip 15 when the door is closed. For purposes of better illustration, the doors of Figs. 3 and 4 are shown in spaced relationship with reference to the box.

My invention provides a device by means of which the sealing strips 15 and 19 may be satisfactorily and economically fastened in place notwithstanding the fact that the fastening means can only be handled outside the box. To this end, I provide a strip 20 which is adapted to be fastened onto the inside surfaces of the flanges 13 and 14 respectively. As applied to the door, these strips are adapted to be attached to the flanges 21 and 22 of the inner and outer plates 16 and 17 respectively. These strips are preferably made from relatively thin sheet metal and are provided at spaced intervals with bolt receiving portions indicated in general at 25 in Fig. 1. Each of such portions preferably embodies a pair of opposing tongues, which are struck upwardly from the body of the strip and which have approximately

V shaped opposing edges for engaging the threads of the bolt that passes therethrough. The strip is suitably heat treated after the formation of the tongues so that the entire strip possesses yielding or spring-like characteristics.

This invention is well suited for the purpose intended, for the strip may be fastened on the inner side of the flanges before the assembly is completed, by the addition of the closure strips 15 and 19 respectively. At such time, the strips may be fastened to the flanges in any suitable manner such as by rivets 26, which extend through openings 27 in the strip, and through registering openings 28 in the flanges. These flanges likewise have bolt receiving openings 29 formed therein to register with openings of the bolt receiving portions 25. If desired, the strip may be fastened onto the flanges by the utilization of tongues 30 which are struck downwardly from the strip, as is shown in Fig. 9, and which are then adapted as shown in Fig. 8 to be passed through openings 31 in the coacting flanges and to be crimped over the outer side thereof. The closure strips 15 and 19 respectively are provided with bolt receiving openings 31 which are adapted to register with the openings 29 and with the portions 25 on the associated strips. Thereupon, threaded bolts 33 are passed through the registering openings and when given a few turns are forced into locking engagement with the spring-like tongues 35, as is shown in Fig. 5. The yielding nature of the tongues allows them to be spread apart to admit the bolt but the spring like characteristics of the metal causes the tongues to grip the threads, and thereby to hold the bolts securely in locking position. Since the strip is securely held against movement with reference to the plates to which they are attached, it is obvious that the closure strips may be fastened in place merely by thrusting the bolts into their openings and giving them one or two turns to lock them.

Where it is desired to fasten together two pieces, one of which may be slightly offset with reference to the associated piece such, for example, as is illustrated in Fig. 7 by the plate 36 and the plate 38, then the strip 20 may be suitably notched as at 40 to compensate for the angle at which the two parts are disposed with reference to each other. In this way, the bolt may be caused to enter the strip at the correct angle and may be effectively locked in place in the manner heretofore described.

It is apparent from the foregoing description that my invention facilitates the assembly of hollow articles, without necessitating the tapping and threading of openings in a retaining bar, with the attendant difficulties of reaming out the coacting openings in the closure plate to effect satisfactory position-

ing of all the bolts. The yieldable tongues which are disposed at spaced intervals coact to guide the bolts into position and the spring-like characteristics thereafter operate to lock them in place.

My invention has accomplished very material savings in the construction of a cabinet, and has eliminated the necessity for the use of wooden frames and the consequent use of screws, which are apt to become loosened or to mar the finish on the exposed part of the cabinet, or other article to which the invention is applied.

I claim:

1. Means for fastening two members together by a plurality of threaded bolts comprising a strip of material carried by one of the members, and having pairs of yieldable tongues arranged thereon at spaced intervals and the other member having openings in registration with the tongues, whereby the threaded bolts may be locked by thrusting them endwise through the openings.

2. A fastening device adapted to be used as a lock nut in fastening two plates comprising a relatively thin metallic strip having pairs of yieldable bolt receiving tongues arranged thereon at spaced intervals.

3. The combination with two members having aligned openings therein adapted to be fastened together, of a strip having a plurality of yieldable tongues disposed in opposing relationship located in alignment with said openings, and threaded bolts passing through the openings and engaging said tongues.

4. Means for fastening a closure on a hollow body having openings therein, comprising in combination a strip member carried by said hollow body and having spaced yieldable bolt receiving portions carried by and disposed within the body, and the closure having openings in registration with the openings in the hollow body and said portions, and bolts extending through the openings and engaging said portions, said bolts being adapted to be locked by a straight longitudinal movement thereof into the openings.

5. In combination, two parts adapted to be fastened together, a strip having groups of bolt receiving tongues struck upwardly therefrom, means between the groups for locking the strip to one of the parts, and the other part having openings in registration with the groups, and bolts passing through the openings and locked to the strip solely by the tension of the tongues thereon.

6. A bolt locking strip having yieldable bolt receiving tongues associated therewith, and having a deformed portion adjacent one edge thereof, to hold the strip at an oblique angle to the part on which it is adapted to rest while a bolt is locked thereto, whereby

the head of the bolt lies flat against one of the parts to be joined.

7. A bolt locking strip adapted to be used as a lock nut in fastening two plates having 5 yieldable bolt receiving tongues thereon, and having other bendable tongues for engaging a support and locking the strip thereto.

8. A fastening device comprising a relatively thin sheet metal strip having yieldable 10 tongues arranged in opposing relationship at spaced intervals thereon and having uniform thickness throughout the length thereof, the strip being sufficiently thin to admit the tongues into the thread of a bolt which 15 passes therethrough, whereby the tongues engage only one turn of the thread.

In testimony whereof, I hereunto affix my signature.

ALBERT H. TINNERMAN.
